CONSTRUCTION OF A REINFORCED CONCRETE DAM

Filed March 5, 1931

FIG. 1

FIG. 4

UNITED STATES PATENT OFFICE

HENRY SORENSEN, OF SAN FRANCISCO, CALIFORNIA

CONSTRUCTION OF A REINFORCED CONCRETE DAM

Application filed March 5, 1931. Serial No. 520,427.

While my invention can be used for any other structure, for which it may be adapted, I have described it applied to the unit of a concrete dam and it consists of a modification 5 of the structure described in my U. S. Patent No. 1,816,797, July 28, 1931.

I have described my invention in the following specification and its accompanying drawings.

10 In the drawings:—

Fig. 1 illustrates my invention applied to horizontally placed reinforcements.

Fig. 2 is an enlargement of Fig. 1 taken at 2—2.

15 Fig. 3 is a plan view of Fig. 2.

Fig. 4 is the enlargement of a reinforcement connection.

Fig. 5 is the enlargement of a tensioning device and a reinforcement gripper.

20 Fig. 6 illustrates my invention applied to vertically placed reinforcements.

Fig. 7 is a section taken at 7—7 on Fig. 6.

Fig. 8 is a modified structure.

25 Similar numerals designate similar parts.

Numeral 1 designates anchors. 2 designates bedrock. 2a the walls of a canyon. 2b a vertical dam unit base. 2c a horizontal dam unit base. 3 designates the tensioning device. 4 designates a unit of the dam. 5

30 designates struts. 6 designates reinforcements. 6a designates heavy reinforcement stubs. 7 designates a reinforcement gripper. 7a designates reinforcement connections. 8, 9, 10 and 11 are parts of tensioning device 3. 12, 13, and 14a are parts of gripper 7. 14 are reinforcement wedges. 15 designates concrete. 16 are corrugations in reinforcements 6. 17 designates casings. 18 designates braces. 19 designates brace wedges. 20 are temporary openings. 21 designates 35 strut wedges. 22 is a loop. 23 is a loop wedge.

Dealing with the part 2—2 of Fig. 1, an enlargement of which is Fig. 2,—while Fig. 3

40 is a plan view of Fig. 2,—I first erect the vertical base 2b on horizontal base 2c, which is resting on bedrock 2. Anchors 1 are cast in base 2b and protrude on both of its sides. After concrete 15, in base 2b, is hard, I attach 45 the one end of reinforcements 6 to the pro-

truding ends of anchors 1 by means of connections 7a.

I may make connections 7a in any other suitable manner, but I have, herein, shown 55 7a consisting of an elongated forged steel ring large enough to hold the two ends of reinforcements 6 and one of the ends of anchors 1. These ends of reinforcements 6 and anchors 1 have split ends into which I drive wedges 14, after these ends of 6 and 1 are placed through elongated ring connection 7a, the end of anchor 1 being placed between the two ends of reinforcements 6. The one of the two reinforcements 6, whose ends are held by connection 7a, stretches out horizontally, 60 while the other of these two reinforcements 6, is bent to connect up with the horizontally extending reinforcement 6, which is attached to the adjacent anchor 1. This adjacent anchor 1 has its two reinforcements 6 attached 65 to itself in the same way as I have just now described, and the bent reinforcement 6,—of this second pair of reinforcements 6,—is connected up with the horizontally extending reinforcement 6—of the first described 70 pairs—in the same manner as above described. The connection between the horizontally extending and the bent reinforcements 6 takes place in the following manner: Between the two ends of these reinforcements 6 I place stub reinforcement 6a, and these two reinforcements 6 and stub 6a are then held together by elongated ring connection 7a, as above described, wedges 14 having been driven into the split ends of 6 75 and 6a. 6a now takes the place of anchor 1. I prefer to give 6a the combined size of the two reinforcements 6, besides giving anchors 1 the same size as reinforcement 6a. In Fig. 3 I have shown strut wedges 21, which, 80 besides serving the purpose of a strut adjuster, may also be used as the means to enable struts 5 to be removed, to which I will 85 make reference below.

In Fig. 4 I have shown an enlarged illustration of the connections 7a between reinforcements 6 and 6a, which I have just now described. The arrows indicate the direction of the tension, to which I will make reference below. It will be understood that 90 95 100

wedges 14 firmly lock the ends of reinforcements 6 and 6a together.

I next place struts 5 on braces 18, so that struts 5 are in line with the horizontally extending reinforcements 6. Struts 5 are placed on both sides of the formations of 6 and 6a, which I have just now described. The one of the ends of struts 5 butt up against base 2b, while tensioning device 3 is placed against the other ends of struts 5. Tensioning device 3 is held in place by means of other braces 18, and I may use wedges 19 to adjust the height of braces 18.

Fig. 5 is an enlargement of tensioning device 3 and reinforcement gripper 7, connected up to stub reinforcement 6a. Tensioning device 3 consists of beams 8, which are held—suitably spaced—together by means of bolts 9. The one side of the flanges of beams 8 butt up against the ends of struts 5, while the other sides of flanges 8 contact washers 10. Washers 10, in turn, contact nuts 11. The one end of reinforcement gripper 7 is threaded to fit nut 11, and is screwed into nut 11 between beams 8, while its other end has inwardly slanting openings 13, against which wedges 14 can operate. Wedges 14 have grooves adapted to grip reinforcements 6a. In order to save metal I prefer to give 7 an elongated box form with openings 12 on all four sides.

I have above described the manner in which I attach the one end of stub reinforcement 6a to the two reinforcements 6, by means of connections 7a, and I now connect the other end of 6a to reinforcement gripper 7 by inserting 6a between the two wedges 14.

After that is done I inject initial tension into reinforcements 6, 6a and the protruding ends of anchors 1 by tightening nuts 11. The strut action of members 5 holds the tension in reinforcements 6 and 6a as well as in the ends of anchors 1.

In the manner which I have just now described, viz:—by having the one end of a reinforcement 6 attached to the one of anchors 1, while that same reinforcement 6 is bent to have its other end attached to the one end of another reinforcement 6, the other end of which is connected to a different anchor 1,—I obtain initially tensioned triangular shape formations of reinforcements 6. These initially tensioned triangular formations, which are firmly held together, prevent concrete 15 from slipping on the steel and clamp concrete 15 together.

I now place casings 17 between struts 5 and the tensioned steel 6, 6a and 1, letting that part of stub reinforcement 6a,—which is attached to gripper 7,—extend through the end casings 17.

I next pour concrete 15 around the tensioned steel 6, 6a and 1, and after that concrete 15 has set I remove tensioning device 3,

by first loosening nuts 11, also removing struts 5, side casings 17 and braces 18.

The strut action of members 5, which has held the tension in steel 6, 6a and 1, then becomes transferred from members 5 to the hardened concrete 15.

I now fill openings 20 with concrete 15, and when the concrete 15,—which is filled in the openings 20,—has set, I remove the end casings 17.

Fig. 3 illustrates that which I have described above.

The ends of stubs 6a now extend from that part of dam 4 which is finished. These extending ends of stubs 6a are now used, instead of anchors 1, for the extended parts of unit 4, this finished part of unit 4 then acting as the base for the yet unfinished parts of unit 4.

k—k and *i—i*, in Fig. 1, illustrate fragments of the finished unit 4 and its base 2b, while *j—j* illustrates another fragment of dam unit 4, which are being added to the finished unit fragment *k—k* and *i—i*.

In *k—k* I have shown tensioning device 3 left embedded in concrete 15, which I prefer to do, in some cases, when the ends of unit 4 are completed. In this case I use stub 6a, instead of gripper 7, to connect steel 6 with tensioning device 3. 6a then having a threaded end that fits nut 11. When constructing this last part of unit 4 I let casings 17 extend to the end of tensioning device 3, in order to enable struts 5 and braces 18 to be removed,—after concrete 15 has set,—in the manner which I have previously described. On Fig. 3 I have with dotted lines indicated the extended casings 17 to which I have just now referred, I remove struts 5 by knocking down wedges 21.

The dotted lines, above *k—k*, *i—i* and *j—j*, indicate the continuation of unit 4, which go upon the lower parts of unit 4, after these lower parts are finished.

The units 4, and their base 2b, stand vertically, side by side, reaching across the canyon between the canyon walls 2a.

In Fig. 6, which illustrates my invention in place ready to receive concrete 15, I have shown my invention applied to vertically tensioned reinforcements. Anchors 1 are here shown secured to horizontal base 2c. Reinforcements 6 are attached to anchors 1, by means of connections 7a, and tensioning device 3 operates in the same manner, as previously described, upon reinforcements 6, 6a and anchors 1. Strut members 5 are placed standing, having their lower ends resting upon base 2c, while their top ends contact tensioning device 3, and casings 17 isolate struts 5 from concrete 15. A fragment of concrete 15 is shown on both of the sides of Fig. 6, with the end of reinforcement 6a extending above concrete 15 on its one side. This extending end of 6a is used, in place of

anchor 1, as the attachment for reinforcements 6, which are used for the upper part of unit 4, that is to be erected upon the lower part, a fragment of this lower part being illustrated in Fig. 6.

Fig. 7 is a section taken at 7-7 in Fig. 6.

I may use other means, than tensioning device 3 and gripper 7, to initially tension the reinforcement steel, and in Fig. 8 I have shown the plan view of a modification of my invention. Due to the fact that I let beams 8 extend laterally, in their relation to the tension in reinforcements 6, these beams 8, when left in concrete 15, exercise the same clamping together action upon concrete 15,—besides preventing concrete 15 from slipping on steel 6,—which the previously described triangular formations of steel 6 do. In Fig. 8 I have shown reinforcement 6 made out of one long rod doubled together in its middle, so that each of the reinforcements 6 consist of a double rod having at its one extreme a loop 22, while its other extreme consists of two ends, which are attached to anchor 1 by means of connection 7a in the manner as previously described. Struts 5 are placed in intermediate beams 8 and base 2b as also previously described. The looped end 22 is thrust between beams 8, and wedges 23 are driven through loop 22 and against those flanges of beams 8, which are opposite to the other flanges of beams 8, that contact strut members 5. Casings 17 are placed between steel 6 and strut members 5.

When wedges 23 are driven reinforcements 6 and anchor 1 become initially tensioned. The strut action of members 5 hold the initial tension, which is injected into 6 and 1. Concrete 15 is thereupon poured around 6 and 1. A fraction of concrete 15 is shown poured around the initially tensioned steel 6 and 1 as well as around part of beams 8 and wedges 23. After concrete 15 has set into hard cohesion with 1 and 6, members 5, braces 18 and casings 17 are removed by knocking down wedges 21. The strut action of members 5 then becomes transferred to concrete 15. The openings 20 are thereupon filled with concrete 15 in the same manner as previously described. The remaining part of beams 8 then becomes embedded in concrete 15, beams 8 forming a permanent part of the structure and clamping concrete 15 together,—to which I have made reference above,—due to the fact that beams 8 extend laterally in the concrete, in their relation to the direction of the tension in reinforcements 6. A similar structure, to the one which I have just now described, is made on the other side of base 2b of Fig. 8, and these two structures,—the one connected up to the one side of base 2b, while the other is connected up to the other side of base 2b,—form unit 4, which then consists of layers, of the horizontally extending reinforcements 6, one above the other and the

whole, or any part, of the dam may consist of these units 4 as shown in Fig. 8. Any one of the units 4, herein described, may be given any desired width.

The main feature of my invention, herein, consists in the arrangements of the initially tensioned steel, which prevent the concrete 15 from slipping upon said steel, besides clamping concrete 15 together. I have shown that in two alternatives, viz:—The triangular steel formations 6, and the laterally extending beams 8.

In my above referred to Patent No. 1,816,797 I have described the advantages, which I obtain by transferring the strut action of members 5 over to concrete 15, after concrete 15 has become hard, besides the protection which the initially tensioned steel gives to concrete 15 against outside pressures.

Various modifications of structure may be made without departing from the spirit of my invention.

I claim:—

1. In the construction of the unit of a reinforced concrete dam, the combination of a plurality of reinforcements the one ends of said reinforcements spaced and anchored to the base of said unit, the other ends of said reinforcements bunched together, a connection holding said bunched ends, said reinforcements initially tensioned by a device attached to said bunched ends, removable means contacting a strut member intermediate said base and said device, concrete embedding said reinforcements, whereby the strut action of said member may be transferred from said member to said concrete, after said concrete has set into cohesion with said initially tensioned reinforcements.

2. In the construction of the unit of a reinforced concrete dam, the combination of a plurality of reinforcements the one ends of said reinforcements spaced and anchored to the base of said unit, the other ends of said reinforcements bunched together, a connection holding said bunched ends, said reinforcements initially tensioned by a device attached by removable means to said bunched ends, a strut member intermediate said base and said device, and concrete embedding said reinforcements, whereby the strut action of said member may be transferred from said member to said concrete, by removing said means, after said concrete has set into cohesion with said initially tensioned reinforcements.

3. In the construction of the unit of a reinforced concrete dam, the combination of a plurality of reinforcements the one ends of said reinforcements spaced and anchored to the base of said unit, the other ends of said reinforcements bunched together, a connection holding said bunched ends, said reinforcements initially tensioned by a device attached by removable means to said bunched ends, a strut member intermediate said base

and said device, concrete embedding said reinforcements, and removable means isolating said member from said concrete, whereby the strut action of said member may be transferred from said member to said concrete, by removing said device and said member, after said concrete has set into cohesion with said initially tensioned reinforcements.

4. In the construction of the unit of a reinforced concrete dam, the combination of a plurality of reinforcements the one ends of said reinforcements spaced and anchored to the base of said unit, the other ends of said reinforcements bunched together, a connection holding said bunched ends, said reinforcements initially tensioned by a device attached to said bunched ends, a strut member intermediate said base and said device, concrete embedding said reinforcements and said device, and means whereby said member may be removed after said concrete has set into cohesion with said initially tensioned reinforcements, so that the strut action of said member may then become transferred to said concrete.

5. In the construction of the unit of a reinforced concrete dam, the combination of the one end of a reinforcement anchored to the base of said unit, said reinforcement initially tensioned by a device attached to its other end, a member adapted to strut said device against said tensioned reinforcement, concrete embedding said reinforcement and said device, said device connectible with adjacent reinforcements by extending into said concrete in a lateral direction from said reinforcement, and means whereby said member may be removed after said concrete has set into cohesion with said reinforcement and said device, so that the strut action of said member may then become transferred to said concrete.

6. In the construction of the unit of a reinforced concrete dam, the combination of the one end of a reinforcement attached to the base of said unit, a tensioning device attached to the other end of said reinforcement, a wedge adapted to initially tension and lock said reinforcement to said device, a member adapted to strut said device against said tensioned reinforcement, concrete embedding said reinforcement and said device, said device connectible with adjacent reinforcements by extending into said concrete in a lateral direction from said reinforcement, and means whereby said member may be removed after said concrete has set into cohesion with said reinforcement and said device, so that the strut action of said member then becomes transferred to said concrete.

HENRY SORENSEN.
